ILLUMINATING LAMP

Friedrich Jaedicke, Berlin-Schmargendorf, Germany, assignor to Julius Pintsch Aktiengesellschaft, Berlin, Germany, a corporation

Application May 19, 1932, Serial No. 612,312, and in Germany December 10, 1931

6 Claims. (Cl. 240—11)

This invention relates to illuminating lamps and is particularly although not exclusively applicable to lamps for railway signal installations of the kind which are capable of being moved up 5 and down on a signal post, e. g. by sliding on rails.

The main feature of the invention resides in the fact that all the gas carrying parts comprising the complete burner arrangement (the gas 10 container with valve, pipe, pressure regulator, burner and so on) are united with a supporting member which is adapted to be mounted in the interior of the lamp. The supporting member with the burner arrangement thereon may be 15 inserted in and withdrawn from the casing as a unitary whole. As a result of the formation of such a unit, the necessity for a flexible tube or pipe between the gas container and burner is avoided. Moreover the mounting of the complete 20 burner arrangement in the lamp is simplified. The complete illumination arrangement may be taken out of the lantern casing and tested in operation without having to disconnect the individual parts. Furthermore, the arrangement 25 permits the light source to be adjusted exactly inside the lantern while the gas container is attached. This last named advantage is especially of importance in railroad signal lamps because such signal lamps are usually provided with parabolic mirrors which require an 30 exact adjustment of the light source with respect to the focal point.

In order that the invention may be clearly understood and readily carried into effect, it will 35 now be more fully described with reference to the example illustrated in the accompanying drawing, in which

Figure 1 is a front elevation of the lamp, partially in section,

Figure 2 is a side elevation thereof, also partially in section, and,

Figure 3 is a plan view of the lamp, the top having been removed.

The gas container 1 with valve 2 is connected 45 by a pipe 3 with the pressure regulator 4, to which the burner 5 is connected. The individual members of the constructional group are removably fitted on a supporting member, e. g. a connecting plate 7. This plate is adapted to be 50 mounted within the casing of the lamp and preferably on the wall of the casing which carries the hanging shoe 13 of the lamp. In this way heavy stresses on the casing of the lamp itself 55 are avoided and the casing may be of thinner sheet material than is usually possible.

An outrigger 8 of the plate 7 has a fork-like connecting piece 9 which embraces the valve 2 of the gas container. The pipe 3 terminates in the connecting piece 9 which is provided with 60 an opening, and there is a corresponding open-

ing in the valve 2, so that when the valve 2 is pressed against the connecting piece 9 by means of the stirrup 10, a gas-tight connection is brought about.

The connecting plate 7, and the casing wall 65 which carries it, have elongated holes 11 which cross one another and through which the fixing bolts 12 are passed. In this manner a precise adjustment of the internal device as regards the focal position of the heated body is made possible. 70 Lamps of this type may be provided with any suitable lens but, as mentioned above, they are usually provided with parabolic mirrors, such as those shown in Fig. 2. It is immaterial what type of directing means is used, but it is important that means be provided for adjusting the 75 burner with regard to the focal position. This is accomplished in my arrangement without disturbing the connections of the complete burner arrangement.

For the damping of oscillations of the internal device, there can also be provided a resilient insertion, e. g. sheet of felt, a leaf spring or the like between gas container and lamp base plate.

The constructional group 1 to 5 and 7 can, after 85 removal of the sheet metal underpart 6, which is detachably fastened on the lamp by any suitable means, be taken out downwards or conversely it can be inserted from below.

Preferably the casing which encloses the constructional group is provided on its under side with an auxiliary foot (stirrup) 14 which is capable of being extended in a direction parallel to the standing surface in order to increase the stability when it is desired to rest the lamp on its 95 base. The lamp shown, as prescribed by railway regulations, is bevelled at one side near the bottom.

What I claim is:

1. An elevatable signal lantern comprising a 100 casing, a burner unit including a gas container within said casing, a supporting member, means for mounting said supporting member within said casing, said burner unit being mounted on said supporting member, whereby said supporting member and burner unit comprise a unitary whole which may be withdrawn from and inserted in said casing as such, said means making provision for horizontally and vertically adjusting the position of the burner in said burner unit with respect to 110 the focal point.

2. An elevatable signal lantern comprising a 115 casing, a gas container, a gas valve on said container, a gas conveying pipe, a pressure regulator, a gas burner, a supporting member, means for mounting said supporting member within said casing and for adjusting its position therein, said gas container, gas valve, gas conveying pipe, pressure regulator and gas burner being mounted on said supporting member.

120

3. An elevatable signal lantern comprising a casing, a shoe on the outside of said casing for attaching the casing to a support, a gas container and a gas burner within said casing, a supporting member, means for mounting said supporting member within said casing adjacent said shoe and for adjusting the position of said supporting member within the casing, said gas container, gas burner and said supporting member forming a unitary whole.

4. An elevatable signal lantern comprising a casing, means secured to the outside of said casing for attaching the lantern to a support, a gas container and a gas burner within said casing, a supporting member, means for mounting said supporting member within said casing adjacent said first named means and for adjusting the position of said supporting member within the casing, said gas container, gas burner and said supporting member forming a unitary whole.

5. An elevatable signal lantern comprising a casing, a gas container, a gas valve on said container, a gas conveying pipe, a pressure regulator, a gas burner, a vertically disposed support-

ing plate, means for mounting said supporting plate within said casing and for adjusting its position horizontally and vertically therein, said gas container, gas valve, gas conveying pipe, pressure regulator, and gas burner being mounted on said supporting plate to form a unitary whole therewith.

6. An elevatable signal lantern comprising a casing, a gas container, a gas valve on said container, a gas conveying pipe, a pressure regulator, a gas burner, a vertically disposed supporting plate, means for mounting said supporting plate within said casing and for adjusting its position therein, a fork-like connecting element attached to said supporting plate, said gas conveying pipe terminating in said fork-like member, and means for pressing said last named element against said valve to form a tight connection, whereby said gas container, gas valve, gas conveying pipe, pressure regulator, and gas burner are mounted on said supporting plate to form a unitary whole therewith.
